TYPEWRITER TABLE

Toshihiko Sakow, 3 Horizon Road,
Fort Lee, N.J. 07024

Filed Nov. 19, 1969, Ser. No. 20,184

Term of patent 14 years

Int. Cl. D6—01

U.S. Cl. D33—14

FIG. 1

FIG. 6

FIG.2

FIG.5

FIG.3

FIG.4

FIG. 1 is a front perspective view of a typewriter table showing my new design;

FIG. 2 is a top plan view thereof;

FIG. 3 is a front elevational view thereof;

FIG. 4 is a side view thereof;

FIG. 5 is a rear perspective view thereof; and

FIG. 6 is a front perspective view of the typewriter table in open position.

I claim:

The ornamental design for a typewriter table, as shown.
